ATTORNEY.

UNITED STATES PATENT OFFICE

WILLIAM A. SEIDEMANN, OF MILWAUKEE, WISCONSIN, ASSIGNOR TO SNAP-ON
WRENCH COMPANY, OF MILWAUKEE, WISCONSIN, A CORPORATION OF WISCONSIN

RATCHET WRENCH

Application filed April 8, 1927. Serial No. 182,107.

The invention relates to wrenches and more particularly to a ratchet wrench for use with interchangeable wrench sockets.

One of the objects of the invention is to provide a ratchet wrench in which the handle is slidably mounted on and revoluble relative to the shank of the wrench whereby the reciprocation and turning of the handle serves to impart a step-by-step rotation to the shank and the nut socket secured thereto.

In those instances where large nuts are to be tightened up and long-handled socket wrenches are used the ratcheting operation is a slow and tedious process and another object of this invention is to provide a quickly operable hand-ratchet arrangement associated with a long-handled wrench whereby the nut may be quickly turned up to a position requiring only a tightening up by the long-handled wrench.

The invention further consists in the several features hereinafter set forth and more particularly defined by claims at the conclusion hereof.

In the drawings Fig. 1 is a side elevation view of a ratchet wrench embodying the invention showing it associated with a long-handled ratchet wrench whose handle is broken away;

Fig. 2 is a vertical sectional view of the wrench embodying the invention;

Fig. 3 is a detail sectional view taken on the line 3—3 of Fig. 1.

In the drawings the numeral 4 designates the squared portion of the shank, 5 a tubular portion of the shank and 6 a flange forming a stop shoulder 7.

The tubular portion 5 is slidably and rotatably mounted in the bore 8 of a tubular handle 9 having a knurled outer surface 10 and a spring 11 is interposed between the end of the bore 8 and the top of said shank. An annular groove 12 is formed in the shank and cooperates with a pin 13 mounted in said

handle and projecting in said bore 8 and groove to limit the extent of reciprocatory movement of the handle and hold the parts in assembled relation with preferably a slight tension of the spring 11 which therefore acts to normally move the handle to its upper po-

sition. The lower end of the handle is bevelled and provided with a series of notches 14 which are adapted to successively register with a ball or other suitable projection 15 that is mounted in a peened over recess 16 in the shank.

With this construction a downward movement of the handle with one of the notches 14 is alined or brought into alined position with the ball 15 effects a clutched engagement between the handle and the shank of the wrench which may then be turned with the handle a partial revolution and then a release of pressure on the handle permits it to move up out of engagement with said ball 15 and then on a slight backward rotation of the handle it is again moved downwardly into engagement with the ball and then turned forwardly these operations being repeated to bring successive notches into engagement with the ball and impart a step-by-step rotation to the shank.

The squared portion 4 of the shank is designed to receive interchangeable wrench sockets, such as the socket 17, and also to take the socket portion 18 of another socket wrench 19 of the long-handled or long lever type, the socket portion 18 being slipped on the shank 4 before the socket 17 is applied thereto. A transverse recess 20 is provided in the lower part of the portion 4 and balls 21 are mounted therein and projected outwardly therefrom by a spring 22 interposed between them, and a ball 23 is mounted in a recess 24 in the upper part of the portion 4 and urged outwardly therefrom by a spring 25. The outer edges of the recesses 20 and 24 are peened over as at 26 so as to limit the outward movement of the ball or balls associated therewith. These spring-pressed balls frictionally engage the sockets so as to prevent them slipping lengthwise of the shank portion of the wrench.

The wrench socket 17 is of conventional form having a squared opening 27 to receive the squared portion 4 of the shank, either as shown in Fig. 2 or when used alone the portion 4 may be moved down until the upper part of the socket engages the shoulder 7.

The socket wrench 19 is also of conven-

tional form in which the socket or wrench-engaging portion 18 has a square hole 28 to receive the squared portion 4 of the shank, said portion 18 being, as shown in Fig. 3, 5 usually formed as a ratchet wheel mounted in the casing 29 with its teeth engaged by spring-pressed pawls 30 in said casing which is at the end of a long handle 31, a portion of which is shown, and by which a powerful 10 leverage is secured on the shank 4 to turn the wrench socket 17 and the nut engaged thereby.

With the wrench 19 applied to the squared portion 4, as shown, in screwing up a nut the 15 handle 9 is successively reciprocated and given a partial turn on each reciprocation to rapidly turn the nut with which the socket 17 is engaged down to a tightening position, the pawls 30 of the wrench 19 permitting 20 this movement. When thus brought to this position the ratchet wrench 19 is then operated in the usual manner to progressively turn the shank 4 and the socket 17 and only a few movements of this wrench 19 are re- 25 quired to securely tighten the nut. Thus time and labor are saved in manipulating and tightening up nuts whose position is such as to necessitate the use of a ratchet wrench. In some instances the wrench 19 may not be used 30 and under these conditions the rapid ratcheting action of the handle 9 brings the nut to the desired position where it may, if necessary, be tightened up with a separate socket wrench or with an ordinary wrench.

35 I desire it to be understood that this invention is not to be limited to any particular form or arrangement of parts except in so far as such limitations are included in the claims.

What I claim as my invention is:

40 1. In a device of the character described, the combination with a wrench-socket-engaging shank, an axially ratcheting handle associated with said shank, and horizontally ratcheting wrench of the lever type having 45 a socket portion detachably secured to said shank.

50 2. In a socket wrench, the combination with a shank adapted for detachable connection with interchangeable sockets, a tubular handle slidably and rotatably mounted for axial association with said shank, a ratcheting connection between said shank and said tubular handle responsive to relative axial movement therebetween, and a lever type 55 wrench operatively connected to said shank for the purpose set forth.

60 3. In a socket wrench, the combination with a shank having a polygonal part for detachable connection with interchangeable wrench sockets, of a lever type socket wrench ratcheted to said shank normal to the axis thereof, a tubular handle slidably and rotatably mounted on said shank, and an axial ratcheting connection between said handle 65 and said shank.

4. In a wrench, the combination with a wrench socket engaging shank, of a tubular handle axially slidable in said shank, a spherical projection on said shank, there being notches conforming to said projection in contour in the peripheral edge of said tubular handle, and spring means for normally disengaging said notches from said projection.

In testimony whereof, I affix my signature.

WILLIAM A. SEIDEMANN.
